US00D665234S

(12) **United States Design Patent**
Bagley

(10) **Patent No.:** **US D665,234 S**
(45) **Date of Patent:** **** Aug. 14, 2012**

(54) **EXPANDING COLANDER**

(75) Inventor: **Justin Bagley**, Seattle, WA (US)

(73) Assignee: **Progressive International Corporation**,
Kent, WA (US)

(**) Term: **14 Years**

(21) Appl. No.: **29/412,715**

(22) Filed: **Feb. 7, 2012**

(51) **LOC (9) Cl.** **07-04**

(52) **U.S. Cl.** **D7/667**

(58) **Field of Classification Search** D7/667,

CLAIM

I claim the ornamental design for the expanding colander, as shown and described.

DESCRIPTION

FIG. 1 is a perspective view of the expanding colander, showing my new design.

FIG. 2 is a top view of the expanding colander.

FIG. 3 is a right side view of the expanding colander, the left side view being a mirror image.

FIG. 4 is a front view of the expanding colander.

FIG. 5 is a back view of the expanding colander; and,

FIG. 6 is a bottom view of the expanding colander.

1 Claim, 4 Drawing Sheets
